UNITED STATES PATENT OFFICE

CARL LUDWIG LAUTENSCHLÄGER, OF FRANKFORT-ON-THE-MAIN, MAX BOCKMÜHL AND GUSTAV EHRHART, OF HOCHST-ON-THE-MAIN, AND ADOLF SCHWARZ, OF FRANKFORT-ON-THE-MAIN, GERMANY, ASSIGNEES, BY MESNE ASSIGNMENTS, TO WINTHROP CHEMICAL COMPANY, OF NEW YORK, N. Y., A CORPORATION OF NEW YORK

MOLECULAR COMPOUNDS OF P-IODO-ETHOXYBENZOIC ACID BENZYLESTER

No Drawing. Application filed April 15, 1926, Serial No. 102,302, and in Germany May 1, 1925.

The present invention relates to new remedies for diseases accompanied by pathologically increased blood-pressure.

It is known that medical science has for a long time endeavored to find therapeutic means for reducing the pathologically increased blood-pressure to its normal pressure or at least lowering it so much that the physical and psychical complaints of the patients are reduced to a minimum. The pharmacologists have made special efforts to find substances which are capable of favorably influencing the hypertension and the vascular spasms without injuriously affecting the human body. Heretofore there have been chiefly used preparations of iodine and spasmolyticæ, among the latter particularly preparations containing a benzyl radical. Furthermore, it has been proposed to use for the purpose in question nitrites and nitro esters by which, however, no satisfactory results were obtained.

During the researches made in this highly important domain of therapeutics it has been ascertained that the derivatives of hydrazoic acid, particularly its organic derivatives have an extremely favorable action on the hypertonic blood-pressure. In spite of their intensive acting power it is, however, not advisable to use the azides alone, because their action is too fugacious owing to the fact that the said azides degraded in the human body and are excreted too quickly.

We have during our own investigations made the remarkable observation that it is possible to realize a much more favorable action than is obtainable by the heretofore used hypotonics, if a small amount (for example 5%) of an azide is caused to interact with the usual hypotonics. The efficacy of the new medicaments is not produced by a simple additive action of the components, but the intensity and duration of their action is greater than the total action of the components, so that there seems to be a potential effect in the sense of Buergi. This assumption explains however only partly the action realized, whereas in particular their protracted stronger action, as compared with that of the usual hypotonics may be ex-

plained by the fact that the azides are capable of entering into a molecular combination with the known hypotonics above mentioned—for instance the benzyl derivatives or purine derivatives—whereby the distributing and excreting properties of the azides are naturally largely altered with the result that the azides obviously remain for a longer time in the human body.

For preparing the new therapeutic agents it is advantageous to render the components homogeneous in a finely subdivided state. A substance of particularly high efficacy is obtained for instance by combining one of the bodies described in German patent specification No. 412,699 of July 30, 1922, with pseudosaccharine azide. The favorable results obtained by testing the new bodies on animals, have been fully confirmed by the observations made with human patients.

The following examples serve to illustrate our invention:

(1) 1.91 parts of p-iodoethoxybenzoic acid benzylester (see German patent specification No. 412,699) and 1.04 parts of pseudosaccharine azide are dissolved in 30 parts of acetone and the solvent is evaporated in vacuo. The remaining substance contains 9.5% of nitrogen and has the probable formula:

(2) In a melt, while it is still warm, of 1.91 parts of p-iodoethoxybenzoic acid benzylester, are carefully dissolved 0.43 parts of carbamic azide. After cooling, the whole mass solidifies into a colorless substance which has the probable formula:

(3) 2.02 parts of iododihydroxypropane 10.

and 1.63 parts of p-hydroxybenzoic acid azide are dissolved in ether and the solvent is then carefully evaporated. The product has the probable formula:

5

(4) Into a solution, which has been prepared in the heat and then somewhat cooled, of 0.9 parts of theobromine in glacial acetic acid are introduced 1.02 parts of hippuric acid azide. The solvent is then carefully evaporated. The product has the probable formula:

20

(5) 0.9 parts of theobromine and 1.17 parts of β -naphthalene sulfonic acid azide are treated as indicated in Example 4. The product has the probable formula:

30

We claim:

1. As new products, the molecular compounds consisting of p-iodo-ethoxybenzoic acid benzylester and an organic azide.

35 2. As a new product, the molecular compound consisting of p-iodo-ethoxybenzoic acid benzylester and pseudo-saccharine azide.

3. As a new product, the molecular compound consisting of about 1.91 parts of p-iodo-ethoxybenzoic acid benzylester and about 1.04 parts of pseudo saccharine azide.

In testimony whereof, we affix our signatures.

CARL LUDWIG LAUTENSCHLÄGER.

Certificate of Correction

Patent No. 1,836,125.

Granted December 15, 1931, to

CARL LUDWIG LAUTENSCHLÄGER ET AL.

It is hereby certified that error appears in the printed specification of the above-numbered patent requiring correction as follows: Page 1, line 32, after the word "azides" insert the word *are*; page 2, after lines 19 to 22 inclusive, strike out the formula and insert instead—

and that the said Letters Patent should be read with this correction therein that the same may conform to the record of the case in the Patent Office.

Signed and sealed this 7th day of June, A. D. 1932.

[**SEAL.**]

M. J. MOORE,
Acting Commissioner of Patents.
